(57) **CLAIM**

The ornamental design for an hair reader, as shown and described.

DESCRIPTION

FIG. 1 is a right side view of a hair reader according to a first embodiment;

FIG. 2 is a rear view of the hair reader shown in FIG. 1;
FIG. 3 is a left side view of the hair reader shown in FIG. 1;
FIG. 4 is a front view of the hair reader shown in FIG. 1;
FIG. 5 is a top view of the hair reader shown in FIG. 1;
FIG. 6 is a bottom view of the hair reader shown in FIG. 1;
FIG. 7 is a first perspective view of the hair reader shown in FIG. 1;

FIG. 8 is a second perspective view of the hair reader shown in FIG. 1;

FIG. 9 is a right side view of a hair reader according to a second embodiment;

FIG. 10 is a rear view of the hair reader shown in FIG. 9;

FIG. 11 is a left side view of the hair reader shown in FIG. 9;

FIG. 12 is a front view of the hair reader shown in FIG. 9;

FIG. 13 is a top view of the hair reader shown in FIG. 9;

FIG. 14 is a bottom view of the hair reader shown in FIG. 9;

FIG. 15 is a first perspective view of the hair reader shown in FIG. 9;

FIG. 16 is a second perspective view of the hair reader shown in FIG. 9;

FIG. 17 is a right side view of a hair reader according to a third embodiment;

FIG. 18 is a rear view of the hair reader shown in FIG. 17;

FIG. 19 is a left side view of the hair reader shown in FIG. 17;

FIG. 20 is a front view of the hair reader shown in FIG. 17;

FIG. 21 is a top view of the hair reader shown in FIG. 17;

FIG. 22 is a bottom view of the hair reader shown in FIG. 17;

FIG. 23 is a first perspective view of the hair reader shown in FIG. 17; and,

FIG. 24 is a second perspective view of the hair reader shown in FIG. 17.

The claimed design is shown in solid lines. The broken lines illustrate portions of the hair reader and form no part of the claimed design.

1 Claim, 6 Drawing Sheets
